UNITED STATES PATENT OFFICE

FRANCIS R. DRAVO, OF EDGEWORTH, AND VERA B. EDWARDS, OF MOON TOWNSHIP,
ALLEGHENY COUNTY, PENNSYLVANIA, ASSIGNEES TO THE DRAVO CONTRACTING
COMPANY, A CORPORATION OF PENNSYLVANIA

MARINE RAILWAY

Application filed March 10, 1931. Serial No. 521,450.

This invention relates to marine railways, and consists in improvements in structure and mode of operation which, overcoming defects and limitations, adapt the railway more fully and more perfectly to the conditions of service and render it more durable and more efficient.

In the accompanying drawings Fig. I is a view in vertical and longitudinal section (taken on the plane I—I of Fig. II) of a marine railway of this invention, installed at the margin of a body of water, as for example a navigable river, and adapted to carry river craft such as steamboats and barges back and forth between a position of flotation in the water and an elevated position on shore, where they are accessible for building, repair, and other purposes; Fig. II is a view to smaller scale, showing the structure in plan; Fig. III is a fragmentary view in vertical and longitudinal section, taken on the plane III—III of Fig. II, to larger scale than Fig. I, and illustrating details of carriage structure and of carriage-moving means; Fig. IV is a fragmentary view, showing in plan parts which in Fig. III are shown in elevation; Fig. V is a view to still larger scale, in vertical and transverse section, on the plane indicated at V—V, Fig. III; Fig. VI is a fragmentary view in vertical and longitudinal section, comparable with Fig. III, illustrating certain details of structure, and serving, together with Fig. III, to illustrate certain features of utility; Fig. VII is a fragmentary view in vertical section, transverse with respect to the extent of the railway, and to still larger scale, illustrating further details of carriage structure; Fig. VIII shows, in side elevation and in horizontal section, details of chain structure; Fig. IX is a view in plan, illustrating to larger scale the carriage-moving means shown in Fig. IV; Fig. X is a view in vertical and longitudinal section, comparable with Fig. I, illustrating to larger scale certain details of structure of the marine railway; Fig. XI is a fragmentary view, illustrating schematically the electrical control panels and their associated control equipment; and Fig. XII is a wiring diagram of one unit of the control equipment, and of

the carriage-moving means associated therewith.

The railway consists of an inclined bed and of tracks, extending upon the bed and up and down the inclination thereof, transversely of the water-line for suitable distances beneath the water on the one hand and up the bank on the other, of cars movable upon such tracks, and of means for moving the cars.

In the railway of this invention the tracks are laid in pairs—1, 1; 2, 2; etc., Fig. II. The two tracks of each pair are spaced apart at a relatively narrow interval—5 feet, for example—and the successive pairs of tracks are properly spaced to suit the intended use. In this instance there are 12 pairs of tracks, spaced at center-to-center intervals of 23 feet. The tracks are laid at a slope of 1:8; and in this case they are about 400 feet long and extend 160 feet beyond the water-line, that is to say, to a depth of 20 feet. The rails rest on parallel steel beams 3 (Fig. V). The bases of the rails and the steel beams on which they rest are held in beams 4 of strongly reinforced concrete. Across the lower end of the railway extends a concrete wall 5, upon which the beams 4 at their lower ends abut. The wall 5 in turn rests in part on a solid line of sheet-steel piling 6, driven in this case through the sedimentary river-bed to rock, to prevent undercutting by river current. Wooden piles 7, driven on a 1:4 batter, underlie so much of the track beams as extends below the water-line; these resist the tendency of the tracks to creep down hill.

A separate carriage 8 travels upon each pair of tracks, and in this installation there are in all 12 carriages. In this case the carriage is of wedge shape and of double box girder construction; it is 48 feet long and at the river end stands 10 feet high. It is provided with lines of double-flanged wheels 81 which engage the tracks 1, 1; 2, 2; etc.

The wheel is integrated with its axle 82, and is trunnioned in bushings 83 which are set in the opposite walls of a box 84 borne by the carriage (Fig. VII). The box surrounds the wheel, and its side-walls depend on either side of the rail which the wheel en-

60

75

95

100

gages; its end walls, which depend to close approximation to the treads of the rails, are of plow shape, as indicated at 184. Suitable packing excludes water from the bearing, 5 and the surrounding box protects the wheel from being clogged or fouled by water-borne drift; its plow-shaped ends serve to clear the track of mud as the carriage moves beneath the water-line.

- 10 Upon each of its upper longitudinal edges the carriage bears a length of 18-inch rolled channel 85, with upturned flanges. These channels constitute slideways and are adapted to receive blocks, in this case timbers 86, 15 which may be held to position during submergence by means of pins 87. In service, the horizontal surfaces of the channels beneath the timbers are greased, and upon withdrawal of the pins 87 a load may be shifted 20 by slippage, in the manner described below.

Each component box girder of each carriage is equipped at the water end with a steel plow 88, to fend off débris as the carriage descends in the water. At the water 25 end each girder is provided additionally with a bumper block 188 of timber. A stop 89, which may be adjustable in position, stands vertically near the land end of the carriage. The carriage may be equipped with a pawl 30 100, to engage a rack 98 suitably set adjacent the tracks.

- Each carriage is raised and lowered upon a single hauling-member, in the form of a chain 9, secured by bridle 90 to the carriage. 35 The chain is trained upon a sprocket-wheel 10 at the land end of the railway. Rollers 99 are set at intervals in fixed standards between the tracks to support the chain. The chain is of sufficient length to permit the carriage 40 to be lowered to the water end of the railway, with some surplus. The otherwise free end of the chain, the end remote from the carriage, is secured to a back-haul line in the form of a steel rope 91 which extends around 45 a sheave 92 at the water end of the railway, and at its farther end is secured to the carriage. The sheave 92 is rotatably borne in an anchorage in the form of a bar 93, adjustable in its effective length. This bar is pivoted, 50 and is of such length that by swinging it the upper end may be raised clear of the water, for purposes of adjustment and for proper attention to the sheave 92. In Fig. III the raised position of bar 93 is indicated in dotted lines.

Fig. VIII illustrates the construction of the hauling-chain. Each link includes four bars 94 of rolled steel, pivoted upon shoulered pins 95, the bars of successive links 60 being interdigitated, as shown in the drawings. Washers 96 are interposed between the bars, to relieve friction when the chain rounds the sprocket-wheel. The material used is most carefully selected and the fabrication is minutely accurate; particularly,

the pivot-holes in the bars 94 are most accurately spaced and shaped. The construction admits of extreme accuracy in dimensions, with close tolerances, to maintain uniformity, to the end that companion carriages shall 70 move on their tracks in unison. Instead of nuts, threaded upon the pins 95, the assembly is made secure by washers 97, welded to place.

Associated with each carriage is a hauling 75 unit, consisting of an electro-motor, with suitable reduction gearing, the last element of which carries the sprocket-wheel 10. In the line of connection is arranged a speed-changing device 12, through the use of which 80 carriage speed may be accelerated, for the movement of empty carriages and light loads. A magnetic brake 13 is associated with the first counter-shaft of each hauling unit, and a hand-brake 14 with the second. 85

The first counter-shaft 15 is tubular, and constitutes a quill upon a line-shaft 16. The line-shaft extends in continuity, and upon it the quill-shafts of the transmission mechanisms of a plurality of the hauling units— 90 and, conveniently, of all of the hauling units—are mounted. Magnetic clutches 17 are provided, one in association with each unit, for uniting and separating at will the quill to and from the line-shaft. 95

The hauling units and the line-shaft with their associated parts are contained in a machinery house 18 which extends across the land end of the railway, and the walls of the machinery house serve as a support for the 100 rails 19 of a service track, upon which a gantry whirler crane 20 travels, to handle material for repair work and material for the new construction which may at times be carried forward on the railway. A service 105 railway 26 extends along the land side of the machinery house.

Entrance doors 21 to the machinery house are provided between the succeeding pairs of tracks 1, 1; 2, 2; etc., and through the roof (of concrete slab construction) hatchways with removable steel covers 22 are formed. These hatchways are arranged, one immediately above each hauling unit, and they are sufficient in size to permit the removal 115 of the hauling unit complete, when required.

The motors, the magnetic clutches, and the magnetic brakes may be made subject to control from a single properly situated station 23 (Fig. II), and by a single operator having clear view of the whole railway. The speed-changing devices, as well, might be made subject to control from station 23; but, as a matter of fact, in the installation which we actually have made, each speed-changing device 12 is severally and manually operable, as is usual with such devices. The hauling units with their quill shafts, the line-shaft and the magnetic clutches, constitute an assembly in which any one hauling 125

unit may be operated alone, or any combination of the whole twelve units may be tied together and made responsive in simultaneous operation to the swinging of a single master switch. A system of signal lights 5 may be provided, to indicate to the operator which particular units are connected for service, and watt meters may be provided, to indicate the magnitude of the load which 10 each motor in operation is carrying. In case any motor is thus revealed to be subject to overload (its associated carriage sustaining an undue portion of the entire burden), that motor may be disconnected from the assembly, and may then be individually driven, 15 until its hauling chain is properly adjusted in its effective length, whereupon it may be restored again to its place in the assembly, and operation of the whole may be resumed. 20 A system of push-buttons may be provided, and, in response to pressure upon one and another of them, the individual carriage may be inched into proper position relatively to another carriage or other association of 25 carriages. Such inching of an individual carriage will ordinarily be done above the water line and before lowering a set of carriages to receive their load. After a floating vessel has been brought to position over a 30 previously lowered set of carriages, further inching may if necessary be performed. Inchng may also be done in case a particular carriage becomes overloaded in course of hauling. It will further be perceived that, 35 when a boat is to be raised whose hull is not flat-bottomed, cradles may be provided to engage the hull and to be engaged immediately by the carriages, and when such cradles are employed, there will be greater likelihood 40 of necessity for inching the carriages after submergence. The controls for the motors, the clutches, and the brakes are provided with the necessary interlocks and with over- 45 load and safety features, to insure unitary operation of any predetermined group of carriages.

A trench 24 is provided for carrying electrical connections from station 23. A feed-line from a suitable source of electric power 50 to the station is indicated at 25.

Electrical control of the nature indicated is illustrated in Figs. XI and XII. This control equipment includes a switchboard 101, a control desk, 102, clutches 17 (cf. Fig. 55 IV), and brakes 18 (cf. Fig. IV). The switchboard carries an accelerating panel 103 and reversing panels 104, of which latter there is one for each motor 11 (again, cf. Fig. IV). The motors drive, as has been 60 explained, the sprocket wheels 10, of which there is one for each carriage. The control is so arranged that, with control switches K closed and with the transfer switch 105 of any motor (there is one such transfer switch 65 for each motor) turned to the position desig-

nated "IND", that particular motor 11 may be run individually, to bring its particular carriage to proper position—as, for instance, to supporting position beneath the hull of a boat.

Referring particularly to Fig. XII, the wires *a* and *b* may be understood to be line wires from a source of direct current, and the wires L1, L2, and L3, may be understood to be the three line wires for the three phases 70 of an alternating current, with the source of which they are connected. When operation is to be brought about switch J is closed, and current flows in the line *a*, *b*. Simultaneously with the closing of switch J, the relay R is 75 closed and alternating current flows through wire L2 to line L21. Alternating current is supplied to line L21 as long as there is direct current flowing in line wires *a* and *b*. In "off" 80 position the master switch 106 connects wire L21 to a wire L23, leading to the coil of a low-voltage protective relay P. The opposite end of the said coil is connected by wire L15 (through the emergency stop switches 85 120 and 121) to wire L14, and thence to the 90 contacts of the overload relay L. As will presently be described, transformers T are associated with two lines, L6 and L4, of the three-phase current supply system for the 95 motor 11. The secondary coils of the transformers T are delta-connected, by means of hot wires *t*; a mechanical tension wire *s* is trained over a pulley *c*; at one end the wire *s* is secured to a tension spring *d*, and at the other end it is secured to the hot wires *t*. The 100 hot wires *t* furnish the load for the secondary coils of the transformers T, and when over-load currents are drawn through the current supply system, the wires *t* heat and expand, 105 spring *d* shifts wire *s* and rotates pulley *c*, lifting the contact arm *e* and breaking connections between line L14 and live wire L1. In brief, the overload relay or circuit breaker L operates on the principle of a hot-wire 110 ammeter. There is an overload relay L for each of the nine motors 11, and the relays (L) are all connected in series.

As mentioned above, the closing of switch J closes relay R, and (the master switch 106 being in "off" position) the relay P is energized, effecting the closing of circuit through wires L21 and L24, and wires L23 and L24. 115

The control switch K is next closed, connecting wire L17 to wire L1 and wire L27 to wire L24, and energizing spring-closed relay 107. Upon such energizing the relay 107 120 opens against the resistance of its spring.

With the mechanism so adjusted, individual operation of the motors 11 is effected as follows: The starting switch 122 is left open, and the transfer switch 105 of the motor to be individually driven is thrown to the individual position "IND." The function of the transfer switch 105 is to transfer the control 125 of its associated motor 11 from the master 130

switch 106 to the hoisting and lowering switches 108 and 109. To effect the raising of the associated carriage (8) the hoisting switch 108 is closed, connecting wire L27 to wire L45; and at the same time (the transfer switch 105 being closed), a current, illuminating red lamp 113, flows through switch 108, wire L45, transfer switch 105, and wire L44. By means of wires L44 and L17 a circuit is closed through the coil of hoist contactor 111. The contactor 111 closes, and as it closes, its control contact 123 unites wire L1 with wire L13; current then flows through the coil of relay 114 to wire L24, and energy is thus supplied to the instantaneously acting contact Q of relay 114, whereby wire L24 is united with wire L28, and the starting contactor 115 is energized, effecting the supply of current at reduced voltage to motor 11. The current flows to the motor 11 by way of wires L1, L2, L3, resistors 125, wires L11, L22, L33, motor knife switch N, wires L4, L5, L6, wires L7, L8, L9, hoist contactor 111, and wires T1, T2, T3. These lines include the primary coils of transformer T. When the starting contactor 115 closes, a circuit is established from the energized wire L1, through auxiliary contact 123 of the hoist contactor 111, through wire L12 to the coil of brake relay 116, thence through the wire L46, and through the contact 124 on contactor 115, to the wire L24. Accordingly, the brake relay 116 closes the circuit running from the line wire a, through fuse a2, the relay contact wire a21, and through the brake-operating coil to the line wire b, thus releasing the brake for operation of the motor 11. After a definite interval, the time-delayed contact V of relay 114 effects the making of contact between wire L24 and wire L29, so that the "running" contactor 117 is energized. Contactor 117 short circuits the resistors 125, and effects the application of full voltage to the motor terminals. When the hoisting switch 108 is released the above-described connections are interrupted and the motor stops.

To lower the carriages individually, the sequence of operation is the same as that required for the individual hoisting of the carriages, except that the lowering switch 109 is closed, which effects the closing of the lowering contact 110 and the energizing of the green light 112. Such operation of contactor 110 reverses the direction of rotation of the motor 11. Otherwise, the operation of the parts is the same as that required for the individual hoisting of the carriages.

When group operation of several motors 60 11 is desired, the controls of the hoisting units which are to be grouped are adjusted as follows: The transfer switches 105 of these motors are thrown to group position "GRP". The starting switch 122 is closed, connecting wire L21 to wire L25. In each unit the trans-

fer switch 105 effects energizing of line L26, whereby the blue light 119 and the coil of clutch relay 118 are energized.

The energizing and consequent closing of relay 118 completes a circuit from line wire 70 a, through fuse a1, through electric-operated clutch 17, and through wire L30 to line wire b. So, the closing of relay 118 energizes the clutch 17, and the motor 11 is united with the line shaft 16. The closing of relay 118 also 75 establishes connection between live wire L1 and wire L16; wire L16 is, however, not in a closed circuit, because spring-closed relay 107 remains open, unless (as will presently appear) the fuses of knife switch K are 80 blown. All motors of the group are in this manner connected to the line shaft.

The master switch 106 is now moved to "hoist" position, and effects connection of wire L21 to wire L43. It will be remarked 85 that wires L25 and L43 are connected to the transfer switches 105 of each motor, so that the master switch controls the operation of each motor unit in the group. The wire L43 is connected to wire L44 by the transfer 90 switch 105 in "GRP" position, and wire L44, accordingly, energizes the hoist contactor 111. The hoisting operation of the group of motors follows, in the same manner as described in individual hoisting. 95

Upon moving the master switch 106 to "lower" position, wire L41 is energized from wire L21, wire L21 being connected through master switch 106, wire L40, and transfer switch 105 to the wire L41. The lowering of 100 the carriages in group operation from this point on is the same as that described for the individual lowering of the carriages.

Upon failure of the supply line voltage, or upon the opening of any of the motor over-load relays (L), or upon the opening of any of the emergency switches 120, 121, the relay P will open and stop operation. When the voltage returns again to its normal value, the master switch 106 must be returned to "off" 110 position before the relay P can be reset to admit of further operation.

While the group of motors is operating, any motor not in the group may, manifestly, be operated individually. The switch 122 115 of that motor may be left open, and then the shifting of the switches 108 and 109 of that motor will, in the manner described, effect operation.

Two or more motors may be operated as a 120 group without clutching to the line shaft. This is effected by opening the switches 122 of the motors to be operated. Switch 106 then controls the operation of those motors.

If, due to a short circuit, or for any other 125 reason, the fuse of any of the control switches K blows out, the associated relay 107 becomes deenergized, and its spring thereupon closes the relay, uniting wires L16 and L12. Thereupon an auxiliary circuit (L16, L12, L46) 130

charges the brake relay 116, and is effective to withhold the brake 13 from application, so that the hauling chain of the unit which has broken down electrically may continue in 5 operation, being controlled by the other units of the group, connected to the line shaft 16.

The intervals between the beams 4 are paved with pavement in the form of reinforced concrete slabs 41; and above the water-line this pavement is stepped. The treads 10 42 of the steps are 2 feet deep; they are spaced at 8-foot intervals; and between the steps extend inclined surfaces 43, with a rise of 1 foot in 6. See Fig. VI. The treads of 15 the steps are used to carry blocking 48, upon which a vessel which has been raised on the railway carriages may be brought to rest—the carriages being moved downward to shift the burden. This is illustrated in Fig. VI.

20 The inclined surfaces 43 which extend between the treads of the steps are adapted to afford easy access to the work, whether sustained on carriages or on blocking, and the slope is sufficiently gentle to permit the moving about upon it of trucks and other carriages.

Covered service trenches, whose position is indicated at 44, Fig. II, are formed in the pavement and extend from the upper end of 30 the railway downward. They are arranged at convenient intervals, and in this instance they are shown to be arranged on the upstream side of alternate pairs of tracks. At their upper ends they connect with a cross-trench, indicated at 45. These trenches 44 are provided, as will be understood, with convenient outlets, and they are serviceable to contain electric conduits and various pipe lines for air, water, steam, etc.

40 Rudder pits, sunk beneath the general level of the pavement, are provided in suitable locations. In this installation rudder pits 46 are provided at both the down-stream and the up-stream sides of the railway, and 45 conveniently at a distance about 35 feet to the land side of the water-line; and an additional rudder pit 47 is provided at the extreme upper end of and on the down-stream side of the railway. These pits afford access, for the ready removal of and installation 50 of rudders of vessels sustained on the railway.

The problem of which the installation described is a solution is the problem of hauling 55 a plurality of carriages upon a marine railway at uniform speed, to prevent undue strain on any one chain, and to prevent extraordinary stresses within the vessel which is being carried. A disadvantage which is 60 inherent in a railway whose hauling units are connected by hand-operated clutches to a line-shaft driven by a single motor is that a large force of men is required to operate it. The usual construction includes a relatively 65 wide carriage having two hauling chains con-

nected to it at its ends. The chains as commonly constructed are not susceptible to such accuracy in manufacture as to forbid minor irregularities in length; and, in consequence, there are tendencies to a skewing of cars and to an unequal loading of the paired chains.

In exemplification of operation, let it be assumed that a towboat 200 feet long, 40 feet wide, and of 1200 tons weight, is to be raised from the water. Due to the shape of the hull, 70 the maximum number of carriages which may be used to advantage is seven; and the distributed load will average about 170 tons per carriage. Due, however, to overhang, the end carriages must sustain loads approximating their capacity of 250 tons, while the interior carriages of the set are less heavily burdened.

The towboat is brought in, broadside to the railway, and is held with shore-lines in, 80 say, fifteen feet of water. If on an even keel, this boat will draw about six feet of water, and as the carriages at the water end are ten feet high, the carriages as they are lowered will abut upon the side of the hull. The carriages before they are lowered are, by the individual driving of their several hauling units, brought to alignment; they then are lowered in unison, the magnetic clutches which connect the motors to the line-shaft 90 being closed. In this lowering operation the back-haul lines are effective. When the carriages have been brought to abutment upon the hull of the boat, the shore-lines are slackened off, and the carriages are by the back-haul lines advanced downward along the tracks. The advanced carriages in their further descent push the vessel off-shore until, in deeper water, they pass beneath the hull. 100 As soon as the carriages so clear the vessel, their movement is arrested, and the vessel is hauled shoreward, above the submerged carriages, until it rests against the stops 89. Lines from the vessel then are secured to the hauling-chains 9 of the two end carriages, to hold the vessel in position until it comes to rest upon the rising carriages.

All of the hauling motors of the carriages involved, having already been connected by the magnetic clutches with the line-shaft 16, 110 are now brought into action, and the carriages travel up the railway and in doing so raise the vessel and sustain its weight. If then the watt-meter readings show an overload on any individual motor, hauling is interrupted, the particular motor is released from its clutch connection to the line-shaft, the carriage with which it is associated is eased off, and then clutch connection is renewed, and the upward united travel of the carriages is resumed.

The vessel may be hauled to the upper end of the railway; or, if a repair job of short duration is to be performed, it may be brought to rest in a lower position. The mag-

netic brakes 13 are serviceable in bringing the carriages severally to and sustaining them accurately in position. When the vessel is to be kept on the carriages while repair work goes on, the hand-brakes 14 of the hauling-units are set. As an additional safety measure, the pawls 100 may engage their racks; and the pawl would be effective to hold a carriage, even if its hauling-chain were removed.

If the repair job intended is one of longer duration, and if the carriages are needed for further work, the boat, raised to a relatively high position, is transferred to blocking. The wood blocking 48 (Fig. VI) is built up, resting upon the level treads 42 of the stepped pavement adjacent the tracks, and engaging the hull, beneath which it is snugly wedged. The carriages upon which the boat has been raised are then pulled away, leaving the boat resting, as shown in Fig. VI, upon the blocking alone. This operation is greatly facilitated by the lubrication of the timbers 86 in their engagement upon the webs of channels 85. (The pins 87 which secured the timbers 86 during submergence of the carriage will, of course, have been withdrawn before the transfer of the load to the blocking is undertaken.)

We claim as our invention:

1. In a marine railway an inclined bed, a plurality of tracks extending upon said bed, a plurality of carriages movable upon said tracks, a plurality of hauling units, one for each carriage, connection between each hauling unit and one of the said carriages, each hauling unit including a prime mover, a source of energy, means for bringing into energy-receiving association any combination of such prime movers and means for establishing connection from said source of energy to the prime movers of such combination.

2. In a marine railway an inclined bed, a plurality of tracks extending upon said bed, a plurality of carriages movable upon said tracks, a plurality of hauling units, one for each carriage, connection between each hauling unit and one of the said carriages, each hauling unit including an electric motor, a source of electric energy, manually controlled means for bringing into energy-receiving association any desired combination of such motors, and manually controlled means for establishing energizing connection from said source to the motors of such combination.

3. In a marine railway an inclined bed, a plurality of tracks extending upon said bed, a plurality of carriages movable upon said tracks, a plurality of hauling units, one for each carriage, connection between each hauling unit and one of the said carriages, each hauling unit including an electric motor, a source of electric energy, two lines of connection between said source of en-

ergy and each of said motors, manually controlled means for bringing into energy-receiving association along one set of such line any desired combination of such motors, manually controlled means for establishing energizing connection from said source through such associated lines to the motors of such combination, and manually controlled means for establishing energizing connection from said source through the lines of the other set to each motor not included in such combination.

4. In a marine railway an inclined bed, a plurality of tracks extending upon said bed, a plurality of carriages movable upon said tracks, a plurality of hauling units, one for each carriage, connection between each hauling unit and one of the said carriages, each hauling unit including a prime mover, a source of energy, means for bringing into energy-receiving association any combination of such prime movers, means for establishing connection from said source of energy to the prime movers of such combination as a unit, means for establishing connection from said source of energy to the other and unassociated prime movers severally.

5. In a marine railway an inclined bed, a plurality of tracks extending upon said bed, a plurality of carriages movable upon said tracks, a plurality of hauling units, one for each carriage, connection between each hauling unit, and one of the said carriages, each hauling unit including a prime mover, a source of energy, means for bringing into energy-receiving association any combination of such prime movers, means for establishing connection from said source of energy to the prime movers of such combination as a unit, means for establishing connection from said source of energy to the other and unassociated prime movers severally, and means for bringing any prime mover into or out of such an association previously established.

6. In a marine railway an inclined bed, a plurality of tracks extending upon said bed, a plurality of carriages movable upon said tracks, a plurality of hauling units, one for each carriage, connection between each hauling unit, and one of the said carriages, each hauling unit including an electric motor, a source of electric energy, two lines of electric transmission from said source to each of said motors, a manually controlled make-and-break device associated with each motor and controlling the completion of circuit from said source through one or the other of the two lines, and a manually controlled make-and-break device additionally controlling the completion of circuit from said source through one of the two lines to each motor.

7. In a marine railway an inclined bed, a plurality of tracks extending upon said bed, a plurality of carriages movable upon said

- tracks, a plurality of hauling units, one for each carriage, connection between each hauling unit and one of the said carriages, each hauling unit including an electric motor, a 5 source of electric energy, a line of electric transmission leading from said source to each of said motors, a shunt line leading from said source and branching to each of said motors, a control switch for said shunt line, a single 10 manually controlled make-and-break device arranged in said shunt line and controlling the completion of circuit through all the branches thereof, a manually controlled make-and-break device associated with each motor and 15 movable to close a break alternately, either in the line first named or in a branch of the shunt line, a second shunt line associated with each of the lines first named and a time switch arranged in each second shunt line, 20 and means subject to the shifting of the control switch and of the single make-and-break device for establishing the line of flow either through the line first named or through the time-switch including shunt line.
- 25 8. In a marine railway an inclined bed, a plurality of tracks extending upon said bed, a plurality of carriages movable upon said tracks, a plurality of hauling units, one for each carriage, connection between each hauling unit and one of the said carriages, each 30 hauling unit including a prime mover, a source of energy, means for bringing into energy-receiving association any combination of such prime movers, for establishing 35 connection from said source of energy to the prime movers of such combination, and, while energy-imparting connection continues with respect to the others, for separating at will from such combination any component prime 40 mover.
- 45 9. In a marine railway an inclined bed, a plurality of tracks extending upon said bed, a plurality of carriages movable upon said tracks, a plurality of hauling units, one for each carriage, connection between each hauling unit and one of the said carriages, each 50 hauling unit including an electric motor and an electrically controlled brake, a source of electric energy, manually controlled means for bringing into energy-receiving association any desired combination of such units, and manually controlled means for establishing energizing connection from said 55 source to the motors and brakes of the units of the combination.
- 60 10. In a marine railway a plurality of hauling units and a line shaft, each unit including an electric motor and an electrical- 65 ly operated clutch for connecting the unit to the line shaft, a source of electric energy, manually controlled means for bringing into energy-receiving association any desired combination of such units, manually controlled means for establishing energizing connection from said source to the motors of such com-
- bination, and manually controlled means for establishing energizing connection from said source to the clutch of each unit.
11. In a marine railway a plurality of hauling members, a plurality of hauling units 70 each including a prime mover, a line shaft, means for connecting and disconnecting at will each unit and said line shaft, and means for driving at will one of said prime movers alone or any two or more of said prime 75 movers simultaneously.
12. In a marine railway a plurality of hauling members, a plurality of hauling units each including a prime mover, a line shaft, a clutch arranged between each unit and said 80 line shaft, and a brake for each unit.
13. In a marine railway an inclined bed, a plurality of tracks extending upon said bed, a plurality of carriages movable upon said tracks, a plurality of hauling members, 85 one for each carriage, connection between each hauling unit and one of the said carriages, a plurality of prime movers, one for each hauling member, a line-shaft, and means for connecting and disconnecting at will each 90 prime mover with said line-shaft.
14. In a marine railway a plurality of hauling members, a plurality of hauling units, one for each hauling member, each unit including an electric motor and driving connection between motor and hauling member, a line-shaft, the said driving connection in each case including a quill upon said line-shaft, and a plurality of magnetic clutches, one for each quill, and adapted to be effective in alternately uniting and separating quill and line-shaft. 95
15. In a marine railway a plurality of hauling members, a corresponding plurality of carriages, to each of which one hauling member is secured, a plurality of hauling units, one for each hauling member, each unit including a prime mover, a line-shaft, and means for connecting and disconnecting at will each prime mover with said line-shaft. 100
16. In a marine railway a track, a carriage movable upon said track, a hauling member secured at its opposite ends to said carriage, rotatable members arranged at opposite ends of said track about which said 110 hauling member is trained, driving means associated with the rotatable member at one end of the track, and a pivoted anchorage upon which the rotatable member at the other end of the track is mounted. 115
17. In a marine railway an inclined bed extending below and above water-level, a track extending upon said bed up and down the inclination thereof, a wheeled carriage movable upon said track, and a hauling member 120 engaging said carriage, the carriage being equipped with otherwise closed and downwardly opening journal-boxes in the opposite walls of which journal-boxes the carriage 125 wheels are journaled. 130

18. In a marine railway an inclined bed extending below and above water-level, a rail extending upon said bed up and down the inclination thereof, a wheeled carriage movable upon said rail, and a hauling member engaging said carriage, said carriage being provided with a journal-box including integral top ends and sides, the opposite side-walls being provided with aligned openings surrounded exteriorly with outstanding flanges, bearing-blocks set in said sleeves, and a wheel with integral axle rotatably mounted on said bearing-blocks.

19. The structure of claim 2, the side-walls of the journal-box in the assembly extending downward and overlying the sides of the rail engaged by the wheel.

20. In a marine railway a plurality of tracks, a machinery house extending transversely of the tracks at one end of the railway, a plurality of hauling members, a corresponding plurality of hauling units, arranged in said machinery house, and a service track mounted upon and borne by said machinery house.

21. In a marine railway an inclined bed, a plurality of tracks extending upon said bed up and down the inclination thereof, a plurality of carriages movable upon said tracks, and hauling members engaging the carriages, the surface of the bed in the intervals between the tracks being shaped to a succession of areas which in the direction of track extent are alternately inclined and level.

22. In a marine railway an inclined bed the continuity of whose surface is interrupted by a succession of transversely extending level steps with inclined areas between, said bed being provided with a plurality of longitudinally extending tracks, carriages movable upon said tracks, and hauling members engaging said carriages.

23. In a marine railway the combination of an inclined bed, a track extending upon said bed, and a wedge-shaped carriage movable upon said track, such carriage presenting to the load a horizontally extending upper surface and being provided on its upper surface with a slideway extending in the direction of carriage travel for a load-engaging block, the inclination of the surface of said bed being interrupted by a horizontally disposed area, affording a base for blocking.

In testimony whereof we have hereunto set
56 our hands.

FRANCIS R. DRAVO.
VERE B. EDWARDS.
